TWO-BUTTON MULTICALL CONTROL SYSTEM

William F. Eames, Edgewood, Pa., assignor to Westinghouse Electric & Manufacturing Company, a corporation of Pennsylvania

Application January 7, 1932. Serial No. 585,256

4 Claims. (Cl. 187—29)

My invention relates to elevator control systems and has particular reference to elevator control systems of the multicall type.

In elevator systems of the multicall type, a plurality of manual control elements, usually push buttons for registering the calls of prospective passengers for the elevator car, are provided at the landings served by the car. These control elements are interconnected with relays for recording the calls until the latter are answered and for controlling the switches of the system to cause the car to start in the direction of landings from which calls have been registered, to stop at, and to restart from, these landings in a predetermined sequence.

The actual sequence in which the calls are answered differs in different systems, depending upon whether the system is of the "one button" or "two button" multicall type, and whether it is of the "through trip" or "reversible" type. There may also be minor variations in the sequence of some systems of the same type. A feature common to the sequences of all multicall systems, however, is that after the car has started in one direction to answer a registered call, it will answer all calls registered at landings in advance of the car, in its direction of travel, before answering any calls registered at landings from which the car is receding.

In the copending application of Luther J. Kinnard, Serial No. 197,279, filed June 8, 1927 and assigned, by mesne assignments, to the Westinghouse Electric Elevator Company, a two-button reversible multicall system is disclosed in which the sequence of response of the car to registered calls has the following characteristics:

1. The car answers all "down" calls when travelling in the "down" direction and answers all "up" calls when travelling in the "up" direction.
2. The car answers the highest "down" call when travelling in the "up" direction before answering other "down" calls and answers the lowest "up" call, when travelling in the "down" direction, before answering other "up" calls, provided that no call is registered for the direction of travel in which the car is moving from landings in advance of the car.
3. The car answers a "down" call from a landing lower or higher than the car and answers an "up" call from a landing lower or higher than the car.
4. Registered calls are cancelled only when answered.
5. If there is an "up" and a "down" call reg-

istered from the same landing, the "up" direction has preference if the car is moving upwardly when it arrives at the floor and the "down" direction has preference if the car is moving downwardly when it arrives at the floor.

The characteristics listed above are all desirable for expeditious and satisfactory service. However, in order to secure all of them, in accordance with the teachings of the Kinnard application mentioned above, it is necessary to provide four floor relays for each landing intermediate the terminal landings, and a floor relay for each of the terminal landings. I have found that the characteristics listed above may all be secured by a novel control circuit in which two floor relays for each landing intermediate the terminal landings and a single floor relay for each of the terminal landings are provided.

It is accordingly an object of my invention to provide a novel elevator control system of the reversible multicall type, in which two floor relays for each floor intermediate the terminal floors and a single floor relay for each of the terminal floors shall be provided.

Another object of my invention is to provide an elevator control system of the two button reversible multicall type in which novel and simple circuits for the registering and cancelling of calls shall be provided.

Other objects of my invention will become evident from the following detailed description taken in conjunction with the accompanying drawings, in which

Figure 1 is a diagrammatic view showing the relationship of certain mechanical and electrical elements of an elevator system embodying my invention.

Fig. 2 is a diagrammatic view of part of the floor selector shown in Fig. 1.

Fig. 3 is a diagrammatic view illustrating the operation of an inductor relay used in the practice of my invention.

Fig. 4 is a diagrammatic view of an elevator control system embodying my invention.

Fig. 5 is a diagrammatic view of the call registering and cancelling circuits for a five-landing elevator system embodying my invention.

Referring to Fig. 1 of the drawings, the apparatus shown therein comprises an elevator car 105 suspended by means of a cable 2 which passes over a hoisting drum 3 to a suitable counterweight 4. The hoisting drum 3 is mounted on a shaft with an elevator motor 5, a spring-applied electro-magnetically-released brake 6 of 110

usual type, and a telemotor transmitter 7 preferably of the self-synchronizing type.

The telemotor transmitter 7 is electrically connected with a telemotor receiver 8 of the same type, in a well known manner, so that any rotation of the armature of the transmitter produces a proportional rotation, in a corresponding direction, of the armature of the receiver 8.

The telemotor receiver 8 serves as a driving device for a mechanical switch or floor selector 9, the purpose of which is to commutate certain circuits of the system in accordance with the position of the car 1.

In the illustrated embodiment of my invention, the floor selector 9 comprises a vertically mounted base panel 10, upon which are secured suitable guide rails 11 for a pair of vertically movable cross-head members 12 and 13. The cross-head members 12 and 13 are mechanically connected together by means of a chain 14 which passes over an idler sprocket 15, rotatably mounted on the base panel 10, and a driving sprocket 16, rotatably supported by means of a casing 17 mounted upon the base panel 10. The casing 17 contains suitable gearing (not shown) for transmitting the motion of the armature of the telemotor receiver 8 to the driving sprocket 16.

The construction so far described is such that movements of the elevator car 1 are reproduced on a smaller proportionate scale as movements of the cross-head members 12 and 13. Although either cross-head member 12 or 13 may move upward in response to upward movement of the car 1, depending upon the phase sequence of the electrical connections between the telemotor transmitter 7 and the telemotor receiver 8, it will be assumed that the telemotor connections are such that the cross-head member 13 moves upward when the car moves upward and covers its entire path of travel from bottom to top while the elevator car 1 is moving from its lower terminal limit to its upper terminal limit.

Referring now to Fig. 2, which shows diagrammatically, the contact elements of the floor selector 9, a pair of rollers 18 and 19, are mounted on the cross-head member 13 in suitable positions to engage rows of contact fingers 20, 30, 40 and 21, 31, 41, respectively. Each of the contact fingers 20, 30, 40, 21, 31, and 41, is biased by suitable means (not shown) so that it is stable in either of two operating positions. The relationship of the rollers and contact fingers is such that when a roller 18, for example, is opposite a contact finger which it controls, such as 30, the contact finger stands in a disengaged position between an upper and a lower contact member *a* and *b* respectively. When, however, the roller 18 is above the contact finger 30, the latter is held by its biasing means in engagement with the lower contact member *b*. When the roller 18 is below the contact finger 30, the latter is held by its biasing means in engagement with the upper contact member *a*.

A plurality of horizontal rows of contact segments 23, 24, 25 and 26; 33, 34, 35 and 36; 43, 44, 45 and 46 and 53, 54, 55 and 56, vertically spaced at intervals corresponding to the distance between floors served by the elevator car 1, are mounted upon the base panel 10 between the guide rails 11. A plurality of movable contact brushes 60, 61, 62, 63, 64 and 65, carried by the cross-head member 13, extend through the cross-head member into frictional engagement with

the horizontal rows of contact segments mentioned above.

The contact fingers 20, 30 and 40 and the contact fingers 21, 31 and 41 are spaced vertically at distances corresponding to the distances between corresponding landings served by the elevator car 1.

The rollers 18 and 19 and the contact brushes 60, 61, 62, 63, 64 and 65 are so positioned on the cross-head member 13, that when the elevator car 1 is level with a floor, such as the third floor, the corresponding contact fingers 30 and 31 stand in neutral position and the movable contact brushes 60 to 65 stand in positions between the rows of contact segments 23, 33, 43, etc., out of engagement with the latter.

Returning to Fig. 1, a pair of inductor relays 1R and 2R, preferably of the type disclosed in the copending application of Harold W. Williams, Serial No. 279,711, filed May 22, 1928 and assigned to the Westinghouse Electric and Manufacturing Company, are mounted on the car 1 in positions to cooperate with sets of inductor plates 1U, 1D, 2U and 2D, of magnetic material, mounted in the hatchway. For simplicity, only one set of inductor plates 1U, 1D, 2U and 2D has been shown, but it will be understood that a set similar to that shown is provided for each landing served by the car, intermediate the upper terminal landing and the lower terminal landing. A set corresponding to inductor plates 1U and 2U is provided for the upper terminal landing, and a set corresponding to inductor plates 1D and 2D, is provided for the lower terminal landing.

The construction and operation of an inductor relay of the type mentioned above, may be understood by reference to Fig. 3, which shows diagrammatically such a relay in connection with an inductor plate and an electric circuit. Referring to Fig. 3, the inductor relay 3R comprises a magnetic structure 3a having overhanging portions 3b and 3c, a central core portion 3d and a pair of lugs 3e and 3f, all of magnetic material. A pair of armatures 3g and 3h of magnetic material, are pivoted to the magnetic structure 3a in such manner that each may engage a corresponding lug 3e or 3f when moved to a horizontal position. A coil 3i, connected in a circuit which includes a suitable source of electricity 3k and a switch 3l, is mounted on the central core portion of the magnetic structure 3a. Each of the armatures 3g and 3h carries a movable contact member of a set of contact members 3UL and 3DL, respectively, and is biased to the position in which the contact members 3UL and 3DL are closed.

As may be seen from Fig. 3, the magnetic structure 3a and the armatures 3g and 3h constitute a divided magnetic circuit, both branches of which include a long air gap between the overhanging portions 3b and 3c and the armatures 3g and 3h, respectively.

The operation of the apparatus shown in Fig. 3 may be set forth as follows: Upon closure of the switch 3l, a magnetomotive force is impressed on the magnetic circuit of the inductor relay, but in the absence of inductor plates, the reluctance of either branch of the magnetic circuit is too high to permit operation of the corresponding armature 3g or 3h. The armatures 3g and 3h, accordingly, remain in the positions in which the contact members 3UL and 3DL are closed.

If the inductor relay 3R is now moved to a position opposite an inductor plate 3D as il-

lustrated in Fig. 3, the reluctance of a branch of the relay magnetic circuit is reduced by the plate, and the corresponding armature 3h moves to the position shown, in engagement with the 5 lug 3f. If now the inductor relay 3R is moved beyond the inductor plate 3D, the armature 3h, nevertheless, remains in the position illustrated because of the leakage flux in the lug 3f. If the inductor relay 3R is now moved so that the left 10 side of the relay passes an inductor plate, the armature 3g moves into engagement with the lug 3e. The armatures 3g and 3h remain in engagement with the lugs 3e and 3f after having been actuated to such positions, regardless of 15 the position of the inductor relay with respect to inductor plates, until the circuit of the coil 3i is broken by the opening of the switch 3L.

Referring now to Fig. 4, which shows diagrammatically, the connections between the 20 electrical elements of Fig. 1 and the remainder of the system, the armature of the elevator motor 5 is connected in a local circuit with the armature and series field winding 70s of a direct current generator 70. The armature of the 25 direct current generator 70 is mechanically connected to the armature of an induction motor 71, having primary windings which may be connected to a suitable alternating current source 72 by means of a manual switch 73.

30 The separately excited field winding 5f of the motor 5 is connected in a motor field circuit 74 to a pair of supply conductors L1 and L2 which serve to supply the direct current used in the control system. The supply conductors L1 and 35 L2 may be connected to a suitable direct current source 75 by means of a manual switch 76. The generator 70 is provided with a separately excited field winding 70f, connected in a generator field circuit 77 to supply conductors L1 and L2, in series with the contact members of a pair of direction switches 78 and 79 and a field resistor 80. The field resistor 80 may be short circuited by contact members of a speed switch 81 controlled by means of speed circuits 82 and 40 83.

45 The release coil of brake 6 is connected in a circuit with contact members of a brake relay 84. This circuit, together with circuits for a relay 85 and a direction maintaining relay 86 of delayed opening type, are joined to form a brake circuit 87, controlled by contact members of the direction switches 78 and 79.

The operating coil of direction switch 78 is 50 connected in an "up" circuit 88 which includes contact members 1UR of the inductor relay 1R, contact members of an "up" direction preference relay 90 and contact members of a starting relay 92. Similarly, the operating coil of direction switch 79 is connected in a "down" circuit 55 89 which includes contact members 1DR of the inductor relay 1R, contact members of a "down" direction preference relay 91 and contact members of the starting relay 92. The "up" and "down" circuits, mentioned above, are joined to 60 form a circuit which includes the coils of a time element relay 93 and the brake relay 84, a resistor 94 and contact members of a door relay 95. The coil of the door relay 95 is connected 65 in a door relay circuit 96 which includes door contact members 97 and gate contact members 98, in a manner familiar to those skilled in the art. In addition to the usual gate contact members 98, which are closed when the gate is closed, auxiliary gate contact members 99 are 70 provided. The auxiliary gate contact members 75

99, are biased to open position, but are closed when the gate is fully open, as shown in Fig. 4. These contact members (99) are connected in a gate circuit 100, with the coil of a gate preference relay 101, of delayed opening type.

80

The direction maintaining relay 86, the time element relay 93 and the gate preference relay 101, which are all of delayed opening type, operate to their energized positions instantaneously upon completion of their respective circuits, but delay, in dropping out after interruption of their circuits for approximately two seconds.

85

The resistor 94 is of such resistance that it passes a current of sufficient value to maintain a direction switch 78 or 79 closed, if either is already closed when the resistor is inserted in the circuit, but insufficient to permit closure of a direction switch while the resistor is included in the circuit.

90

Either the "up" direction preference relay 90 or the "down" direction preference relay 91 may be closed in response to completion of one of a plurality of closing circuits 102, 103 and 104, each including contact members of a set of floor relays 121, 122, 131, 132, 141 and 142, and one of the contact fingers 20, 30 or 40 of the floor selector 9. Holding circuits 106 and 107 may be established for the direction preference relays 90 and 91 respectively, by the gate relay 101 or the time element relay 93. The holding 100 circuits 106 and 107 each include a resistor 108 and 109, respectively, for limiting the current in the corresponding holding circuit to a value sufficient to maintain the corresponding direction preference relay closed when it has been 110 previously closed in response to completion of a closing circuit 102, 103 or 104, but insufficient to cause closure of the relay.

95

The purpose of the floor relays 121, 122, 131, 132, 141 and 142 is to record the calls of prospective passengers at the floors and of passengers in the car, until the calls are answered. Although for simplicity, only three sets of floor relays, corresponding to the second, third and fourth floors, have been illustrated in Fig. 4, 120 it will be understood that an "up" floor relay and a "down" floor relay are provided for each floor intermediate the terminal floors. A "down" floor relay is provided for the upper terminal floor and an "up" floor relay is provided for the 125 lower terminal floor. The operation of an entire set for a system serving five floors, including the terminal floor relays, will be hereinafter described in connection with Fig. 5.

125

Returning to Fig. 4, the floor relays 121, 122, 130 131, 132, 141, and 142 are each provided with a closing coil c, designed to close the relay, and a demagnetizing coil d designed to produce a magnetomotive force in opposition to the magnetomotive force of the closing coil and sufficient to cause the relay to open when the closing coil is energized and the full voltage of supply conductors L1 and L2 is impressed upon the demagnetizing coil; but insufficient to cause the relay to open when a voltage materially less 135 than the full voltage of supply conductors L1 and L2 is impressed upon the demagnetizing coil.

140

Closing circuits for the "up" floor relays 121, 131 and 141 may be completed through "up" 145 push-buttons 123, 133 and 143, located at the corresponding floors, conductors 124, 134 and 144 respectively, and a conductor 155. Similarly, closing circuit for the "down" floor relays 122, 132 and 142 may be completed through 150

"down" push buttons 125, 135 and 145, conductors 126, 136, and 146 and the conductor 155. Holding circuits for each of the floor relays 121, 122, 131, 132, 141 and 142 may be completed through conductor 156, contact members of the corresponding relay, its closing coil *c* and the conductor 155.

A plurality of car push buttons 127, 137 and 147, one corresponding to each floor served by the car, are mounted in the car. The car push-buttons 127, 137 and 147 may each be connected to the closing coil of either the "up" or "down" floor relays for the corresponding floor, by means of the contact fingers 21, 31 or 41, of the floor selector 9.

A pair of interlock relays 157 and 158 are provided for interlocking the direction preference relays 90 and 91, so that the latter cannot both be closed at the same time. The interlock relays 157 and 158 operate instantaneously upon energization of their coils, but delay for approximately two seconds after deenergization before reclosing their contact members.

The coil of the starting relay 92 is connected in a starting circuit 159 which includes back contact members of each of the floor relays 121, 122, 131, 132, 141 and 142.

A stopping circuit 165, which includes the windings 1L and 2L of the inductor relays 1R and 2R and the operating coil of a cancellation relay 166, may be completed by contact members of any of four stopping relays 160, 161, 162 and 163. The coils of the stopping relays 160, 161, 162 and 163 are connected to the movable contact brushes 60, 61, 62 and 63, respectively, of the floor selector 9.

Each of the "up" floor relays 121, 131 and 141 is provided with contact members for connecting an extreme left contact segment 33, 43 and 53, respectively, to supply conductor L2, through conductors 167, 168 and 169, respectively, and part of the starting circuit 159. Similarly, each of the "down" floor relays 122, 132 and 142, is provided with contact members for connecting an extreme right contact segment 26, 36 and 46, respectively, to supply conductor L2, through conductors 172, 173 and 174, respectively, and part of a common circuit 156.

The operation of the system shown in Fig. 4 may be set forth as follows: Preliminary to control of the car in response to car or hall push buttons, the manual switches 73 and 76 are closed. Upon closure of switch 73, the induction motor 71 is connected to the alternating current source 72 and accelerates to running speed in the usual manner. Upon closure of the switch 76, the supply conductors L1 and L2 are connected to the direct current source, and the motor field circuit 74, the starting circuit 159 and the gate circuit 100 (assuming that the car gate is open) are completed. The field winding 5f of motor 5 now builds up to its full value. The starting relay 92 operates to open its contact members in response to completion of the starting circuit 159. The gate preference relay 101 closes in response to completion of the gate circuit 100 to complete the holding circuits 106 and 107 for the direction preference relays 90 and 91, respectively. The direction preference relays 90 and 91 do not close at this time, however, as the resistors 108 and 109 limit the current to a value insufficient to operate the relays, as previously explained.

Operation of the car 1 may now be initiated by means of the push buttons 123, 125, 127, etc.

The parts are shown in the positions they assume when the car is at the third floor, and the car gate and hatchway door for the third floor are open. If a prospective passenger enters the car at the third floor and presses the push button 147 corresponding to the fourth floor, a circuit for the "up" floor relay 141 is completed through conductor 144, the closing coil of floor relay 141 and conductor 155.

The floor relay 141 closes to interrupt the circuit 172 by means of its lowermost contact members; to establish a holding circuit for itself through its contact members *e*; to connect the contact segment 53 to the supply conductor L2 through conductor 169 and the starting circuit 159; to interrupt the starting circuit 159 and to complete a closing circuit 104 for the up-direction preference relay 90. In response to interruption of the starting circuit 159, the starting relay 92 drops out to close its contact members in the "up" circuit 88 and in the "down" circuit 89.

Upon completion of the closing circuit 104, the "up" direction preference relay 90 closes and the interlock relay 157 operates to open its contact members in the circuit of its "down" direction preference relay 91. The "up" direction preference relay 90, in closing, partially completes a circuit for the stopping relay 161 by means of its lowermost contact members; partially completes a circuit for the stopping relay 163; and partially completes the "up" circuit 88.

If the hatchway door for the third floor is now closed, the corresponding door contact members 97 close to partially complete the door relay circuit 96. If the car gate is now closed, the gate circuit 100 is interrupted at the auxiliary gate contact members 99, and the door relay circuit 96 is completed at the gate contact members 98.

In response to interruption of the gate circuit 100 the gate preference relay 101 is deenergized but does not immediately drop out because of its time element operation described above. In response to completion of the door relay circuit 96, the door relay 95 closes to complete the "up" circuit 88.

Upon completion of the "up" circuit 88, the "up" direction switch 78, the time element relay 93 and the brake relay 84 close. The brake relay 84, in closing, partially completes a circuit for the release winding of the brake 6. The time element relay 93, in closing, completes the holding circuit 106 for the "up" direction preference relay 90, independently of contact members of the gate preference relay 101.

The "up" direction switch 78 in closing, completes the speed circuit 82, the brake circuit 87 and the generator field circuit 77.

In response to completion of the speed circuit 82, the speed switch 81 operates to open contact members in the circuit of winding 1L of the inductor relay 1R and to short circuit the field resistor 80. Upon completion of the brake circuit 87, the brake 6 is released, the relay 85 closes to partially complete the stopping circuit 165 and the time element relay 86 operates to remove the short circuit from the resistor 94. The resistor 94 now limits the current in the "up" circuit 88 to a value sufficient to maintain the direction switch 78, the time element relay 93 and the brake relay 84 operated, but insufficient to cause reclosure of any of these switches if the "up" circuit 88 should be interrupted and reclosed.

As the generator field circuit 77 is now energized and the field resistor 80 is short-circuited, the voltage of generator 70 builds up to its maximum value, and the motor 5 accelerates to full speed. While the motor 5 is running, the cumulative series winding 70s of the generator 70 operates to maintain the speed of motor 5 constant in a well known manner.

As the car moves upwardly, the moving contact brushes 60 to 65 inclusive, of the floor selector 9 move upwardly into engagement with the contact segments of the floor selector 9 which are immediately in advance of them.

Upon engagement of the contact brush 61 with the contact segment 44, a circuit for the stopping relay 161 is completed from supply conductor L1 through the lowermost contact members of the "up" direction preference relay 90, the operating coil of stopping relay 161, contact brush 61, contact segment 44, the demagnetizing coil *d* of the floor relay 141, contact members *e* of the floor relay 141, and conductor L2. It will be noted that the opening coil *d* of the floor relay 141 is included in this circuit. However, the floor relay 141 does not drop out at this time, as the current in the circuit is limited by the presence of the operating coil of the stopping relay 161.

The stopping relay 161 closes to complete the stopping circuit 165. In response to the completion of the stopping circuit 165 the winding 2L of the inductor relay 2R is energized, and the cancellation relay 166 closes.

The cancellation relay 166, in closing, establishes a holding circuit for itself independent of the contact members of stopping relay 161; partially completes a circuit to the contact brush 64; short circuits the operating coil of the stopping relay 161; short circuits the operating coil of the stopping relay 162; and partially completes a circuit to the contact brush 65. Upon the short circuiting of the operating coil of the stopping relay 161, the stopping relay drops out and the opening coil *d* of the floor relay 141 is energized sufficiently to cause the relay 141 to drop out.

The car continues upward at full speed until the inductor relay 2R arrives at a position opposite the inductor plate 2U for the fourth floor. When this occurs, the contact members 2UR of the inductor relay 2R open to interrupt the speed circuit 82. The speed switch 81 drops out to insert the resistor 80 in the generator field circuit 77 and to complete a circuit for the winding 1L of the inductor relay 1R.

The insertion of the field resistor 80 in the generator fluid circuit 77 reduces the excitation of the generator 70 and causes the motor 5 to operate at low speed.

The car continues upward at low speed until the inductor relay 1R arrives at a position opposite the inductor plate 1U for the fourth floor. When this occurs, the contact members 1UR of the inductor relay 1R opens to interrupt the "up" circuit 88 to thereby cause the "up" direction switch 78 and the brake relay 84 to drop out. The time element relay 93 is now deenergized, but does not immediately drop out because of its time element feature, mentioned above. The brake relay 84 in dropping out, interrupts the circuit of the release winding of brake 6 to thereby cause the brake to be applied.

The "up" direction switch 78, in dropping out, 75 interrupts the generator field circuit 77 and the

brake circuit 87 and opens its contact members in the speed circuit 82, which has already been interrupted by the contact members 2UR of the inductor relay 2R.

The generator voltage is now reduced to zero, and the motor 5 is rapidly brought to rest by the action of the brake 6. The car is now at the fourth floor. If, during the two-second interval before the time element relay 93 opens, the passenger in the elevator car opens the car gate, the "up" direction preference will be maintained. If, however, the passenger does not open the car gate before the time element relay 93 drops out, the "up" direction preference will be lost by the interruption of the holding circuit 106, and the car may be operated in either direction in response to further calls.

Assuming that the passenger opens the car gate within the time limit determined by time element relay 93, the gate circuit 100 is completed at auxiliary contact members 99, and the gate preference relay 101 closes to maintain the holding circuit 106, independently of contact members of the time element relay 93. The "up" direction preference will then be maintained until the car gate has been closed and the two-second interval necessary for operation of the gate preference relay 101 has expired. If at any time during this interval, calls for floors above the fourth are registered the car will start upwardly. If no such calls are registered before the gate preference relay 101 drops out, then the circuit for the "down" direction preference relay 91 may be completed in response to operation of any of the floor relays for floors below the fourth floor.

It will be noted that contact brush 61 upon engagement with an energized segment 44 of the floor selector 9 initiated a stopping operation of the elevator car at the next succeeding floor, and also completed a circuit for deenergizing the floor relay 141 for the "up" direction. The contact brush 62 performs a similar function of stopping the car in response to "down" calls when the car is moving downwardly and of cancelling "down" calls by deenergizing the corresponding "down" floor relays. The contact brush 60 performs the function of initiating a stopping operation for the car in response to "up" calls when the car is moving downwardly. The contact brush 65 operates to cancel "up" calls when the car is moving downwardly. The contact brush 63 operates similarly to the contact brush 60, except that it causes the car to stop in response to "down" calls when the car is moving upwardly. The contact brush 64 operates to cancel "down" calls when the car is moving upwardly in a manner similar to contact brush 65.

Turning now to Fig. 5 which shows the set of floor relays for the second, third and fourth floors, and also a terminal floor relay 111 for the first floor and a terminal floor relay 152 for the fifth floor, the sequence of operations upon the occurrence of a plurality of calls may now be explained. In Fig. 5, the functions of the contact brushes 60 to 65 inclusive are indicated by legends.

The parts are shown in the positions they assume when the car is at the third floor. Assuming that the car button 147 has been pressed to initiate the operation of the elevator car in the "up" direction, as described in connection with Fig. 4, and that shortly after the car has started upwardly in the manner described, the push but-

tons 123, 133, 135 and 153 are simultaneously operated, the sequence of operations is as follows: In response to closure of the push button 123, the floor relay 121 closes and completes a holding circuit for itself in the manner previously described in connection with floor relay 141. The floor relays 131, 132 and 152 close similarly.

- 10 The floor relays 121, 131, and 141 are now closed in response to "up" calls for the second, third, and fourth floors, the floor relays 132 and 152 are closed in response to "down" calls for the third and fifth floors, and the car is between the third and fourth floors moving upwardly.
- 15 The contact segments 24, 34, 44 and 54 are now connected at the supply conductor L1 through the opening coils of the floor relays 121, 131, 141 and 152, respectively. The contact segment 33 is connected to the supply conductor L2 through contact members of floor relay 121, conductor 167 and the starting circuit 159. The contact segments 43 and 53 are not similarly energized, however, as the floor relay 121 has interrupted the starting circuit 159 at a point in advance of the conductors 168 and 169. The contact segment 45 is connected to the supply conductor L2 through the demagnetizing coil of the "down" floor relay 132. However, the contact segment 36 is not connected to the supply conductor L2, as the circuit 156 is interrupted at a point in advance of the conductor 173.

30 As the car moves upwardly, the contact brush 61 engages the contact segment 44 to initiate an automatic stopping operation at the fourth floor in a manner described in connection with Fig. 4. As a call for the fifth floor is registered, the "up" direction preference is not lost, and upon restarting of the car, the direction of movement will be upwardly.

- 35 40 After the call at the fourth floor has been answered, the car accordingly moves upwardly until the contact brush 61 engages the energized contact segment 54. An automatic stopping operation similar to that described is now initiated for the fifth floor. When the car arrives at the fifth floor, as no calls for floors above the fifth can be registered, the "up" direction preference is lost, the "up" direction preference relay 90 drops out, and a circuit for the "down" direction preference relay 91 is completed through one of the closing circuits 102 or 103.

45 The car then starts downwardly and continues downwardly until the contact 62 engages the energized contact segment 45. When this occurs, an automatic stopping operation for the third floor is initiated, and the car is brought to rest at the third floor in the same manner as heretofore described in connection with the stopping operation at the fourth floor.

- 50 55 After the call for the third floor has been answered, the car starts downwardly as the "down" direction preference is maintained by the "up" floor relay 121. It will be noted that both "up" and "down" floor relays are effective to initiate a starting operation in the down direction, if the car is above the floor for which the call is registered. Similarly, both "up" and "down" floor relays may initiate a starting operation in the "up" direction if the car is below the floor for which the call is registered.

60 65 70 75 As the floor relay 121 is closed the car starts in the downward direction, and answers the "up" call corresponding to the "up" floor relay 121 for the second floor in preference to

the "up" call corresponding to the "up" floor relay 131 for the third floor.

75 80 After the call for the second floor has been answered, in the manner previously described, and the "up" floor relay 121 has been deenergized, the only remaining call is the corresponding to the "up" floor relay 131 for the third floor. The "down" direction preference is accordingly lost, and the car restarts in the "up" direction to answer the "up" call corresponding to the "up" floor relay 131. When the "up" floor relay 131 drops out, all of the calls have been answered and the "up" direction preference is maintained for a two-second interval by the time element relay 93. After the expiration of the two-second interval, the car may be operated in either direction in response to further calls.

85 90 95 100 I do not intend that the present invention shall be restricted to the specific structural details, arrangement of parts, or circuit connections herein set forth, as various modifications thereof may be effected without departing from the spirit and scope of my invention. I desire therefore that only such limitations shall be imposed as are indicated in the appended claims.

105 I claim as my invention:

1. In an elevator-control system, an elevator car operable in a hatchway past a plurality of floors; motive means for said car; a plurality of floor relays corresponding to said floors, each of said floor relays having a closing coil, an opening coil and means effective upon energization of said closing coil for completing a holding circuit for said relay and effective upon energization of said opening coil for interrupting said holding circuit; means for selectively energizing said closing coils to register calls for said car; starting means for controlling said motive means to start said car; stopping means for controlling said motive means to stop said car at floors for which calls have been registered; direction preference means for causing said starting means, when operated, to start said car in the direction in which it last travelled; means for rendering said preference means ineffective when said car is at any of said floors and no calls are registered for floors in advance of said car in the direction in which it last travelled; and means effective upon operation of said stopping means for energizing the opening coil of a floor relay corresponding to the floor at which said car stops.

- 110 115 120 125 130 135 140 145 150 2. In an elevator-control system, an elevator car operable in a hatchway past a plurality of floors; motive means for said car; a plurality of floor relays corresponding to said floors, each of said floor relays having a closing coil, and opening coil and means effective upon energization of said closing coil for completing a holding circuit for the relay and effective upon energization of said opening coil for interrupting said holding circuit; means for selectively energizing said closing coils to register calls for said car; starting means controlled by said floor relays for controlling said motive means to start said car in the direction of a floor for which a call has been registered; stopping means for controlling said motive means to stop said car at floors for which calls have been registered; direction preference means for controlling said starting means to give preference to calls for floors in advance of said car in the direction in which it last travelled; means for rendering said

preference means ineffective when said car is at any of said floors and no calls are registered for floors in advance of said car in the direction in which it last travelled; and means effective upon operation of said stopping means for energizing the opening coil of a floor relay corresponding to the floor at which said car stops.

3. In an elevator-control system, an elevator car operable in a hatchway past a plurality of floors; motive means for said car; a plurality of floor relays corresponding to said floors, each of said floor relays having a closing coil, an opening coil and means effective upon energization of said closing coil for completing a holding circuit for the relay and effective upon energization of said opening coil for interrupting said holding circuit; means for selectively energizing said closing coils to register calls for said car; starting means controlled by said floor relays for controlling said motive means to start said car in the direction of a floor for which a call has been registered; means for preventing operation of said starting means while said car is being loaded or unloaded; stopping means for controlling said motive means to stop said car at floors for which calls have been registered; direction preference means for controlling said starting means to give preference to calls for floors in advance of the car in the direction in which it last travelled; means for rendering said preference means ineffective when said car is at any of said floors and no calls are registered for floors in advance of said car in the direction in which it last travelled; and means effective upon operation of said stopping means for energizing

the opening coil of a floor relay corresponding to the floor at which said car stops.

4. In an elevator-control system, an elevator car operable in a hatchway past a plurality of floors; motive means for said car; a plurality of floor relays corresponding to said floors, each of said floor relays having a closing coil, an opening coil and means effective upon energization of said closing coil to complete a holding circuit for the relay and effective upon energization of said opening coil to break said holding circuit; means for selectively energizing said closing coils to register calls for said car; starting means controlled by said floor relays for controlling said motive means to start said car in the direction of a floor for which a call has been registered; stopping means for controlling said motive means to stop said car at floors for which calls have been registered; direction preference means for controlling said starting means to give preference to calls for floors in advance of said car in the direction in which it last travelled; means for preventing operation of said starting means for a predetermined interval of time after operation of said stopping means; means for rendering said preference means ineffective when said car is at any of said floors and no calls are registered for floors in advance of said car in the direction in which it last travelled; and means effective upon operation of said stopping means for energizing the opening coil of a floor relay corresponding to the floor at which said car stops.
